United States Patent Office.

JAMES NEWMAN, OF PORTLAND, MICHIGAN.

Letters Patent No. 92,087, dated June 29, 1869.

IMPROVEMENT IN TURBINE WATER-WHEELS.

The Schedule referred to in these Letters Patent and making part of the same.

To whom it may concern:

Be it known that I, JAMES NEWMAN, of Portland, in the county of Ionia, and State of Michigan, have invented a new and useful Improvement in Turbine Water-Wheels; and I do declare that the following is a true and accurate description thereof, reference being had to the accompanying drawings, and to the letters of reference marked thereon, and being a part of this specification.

Figure 1 is a perspective view, with gate closed.

Figure 2 is the same, with the gate open.

Figure 3 is a perspective of the cylinder, with buckets.

Figure 4 is a plan view of the wheel, without gate, and one-half of cap removed.

Figure 5 is a horizontal section of bearing.

Figure 6 is a vertical section of the same.

Figure 7 is the lever and sleeve for operating the gate.

Like letters indicate like parts in each figure.

The nature of this invention relates to an improvement in the construction of turbine water-wheels, with central discharge; and consists in a new construction of buckets in connection with a cylindrical hub; also, in a new and peculiar gate, by which the feed of water to the wheel is regulated, and in the peculiar arrangement of its various parts, the whole forming a wheel which uses the water first by direct action and reaction on the same bucket, thereby obtaining greater power from the same amount of water than can be had otherwise.

A, in the drawings, are the guides which conduct the water from the flume on to the buckets, in the direction of the line of motion, and are rigidly secured at top to the ring B, and at bottom to the projecting flange C, of the case D.

E are the buckets, each cast in one piece, of the form shown in fig. 3, so that the water has a direct action upon the perpendicular portion thereof, and a reaction upon the curved incline of the lower part of said bucket.

F is a cylindrical hub, provided with flange G, to extend over the top of the buckets, which should be of the same width of said flange.

The buckets are secured to this cylindrical hub, which is closed at the bottom, and secured to the vertical shaft H.

I is a cap, made in two or more sections, fitting closely together, and secured in place by being bolted to the ring B. The centre of this cap rises in the shape of a hollow tube, surrounding the vertical shaft, as shown in fig. 4, and is provided with a shoulder, J, upon which sets the prolongation K, of the skeleton-box L, which surrounds the vertical shaft H.

When repairs to the hub or buckets are necessary, any section of the cap may be removed, by which means easy access can be had to the interior of the wheel. By removing the whole cap, the hub and buckets may be entirely removed without disturbing the case.

The perpendicular portion of the buckets should be equal to the width of the guides A, the curve in the buckets commencing below the line of the bottom of said guides.

The skeleton box L, is provided with set-screws N, by means of which the wooden blocks M are held in position against the shaft H, to retain it in a vertical position. The skeleton boxes are cast in one piece, of the form shown in the drawings.

O is a circular metallic band, of sufficient width to cover the openings to the guides, its bottom edge resting upon the flange C.

Standards P are secured to and rise from the cap I; to the upper ends of these standards are fulcrumed the arms or levers Q.

The outer ends of these arms enter slots in lifting-braces R, the lower ends of which are secured to the band O.

The inner ends of these arms enter proper slots in the sleeve S, which works upon the shoulder T of the cap.

A lever, U, secured to this sleeve, and fulcrumed to a similar standard, furnishes the means of raising or lowering the band O, the whole forming a new, novel, and very efficient gate for the exclusion or admission of water to the wheel; one very easily operated, because the pressure is equal all around it.

V shows the bottom of a flume, in section, showing the manner of setting this wheel, the case D projecting through said bottom, the under side of the flange C resting upon said bottom.

The lower end of the shaft H, is secured in the usual manner.

What I claim as my invention, and desire to secure by Letters Patent, is—

The bucket E, above described, in combination with the cylindrical hub F, and the flange G, when constructed and operating as above set forth.

Also, the band-gate O, standards P, arms Q, sleeve S, lifting-braces R, and lever U, when arranged and operating substantially as set forth, shown, and described.

JAMES NEWMAN.
